DESCRIPTION

CPC F02M 37/04; F02M 37/14; F04B 53/92;
F04B 1/005

FIG. 1 is a front/right side isometric view of a central ring portion of a positive displacement pump;

See application file for complete search history.

FIG. 2 is a front elevational view of the pump of FIG. 1;
FIG. 3 is a rear elevational view of the pump of FIG. 1;
FIG. 4 is a right side elevational view of the pump of FIG. 1;

(56) **References Cited**

FIG. 5 is a left side elevational view of the pump of FIG. 1;
FIG. 6 is a top plan view of the pump of FIG. 1; and,
FIG. 7 is bottom plan view of the pump of FIG. 1.

U.S. PATENT DOCUMENTS

The broken line showing of elements is included for the
purpose of illustrating environmental matter and forms no
part of the claimed design.
